UNITED STATES PATENT OFFICE.

HAROLD EDWARD SHERWIN HOLT, OF FARNBOROUGH, ENGLAND.

PARACHUTE APPARATUS.

Application filed March 13, 1922. Serial No. 543,538.

To all whom it may concern:

Be it known that HAROLD EDWARD SHERWIN HOLT, subject of the King of Great Britain and Ireland, and a resident of "The 5 Grange," Farnborough, in the county of Hampshire, England, whose post-office address is "The Grange," Farnborough, Hampshire, England, has invented certain new and useful Improvements in Parachute 10 Apparatus, of which the following is a specification.

This invention relates to a quick emergency release safety coupling and has for its object primarily to provide facilities for 15 quickly releasing a parachute from its load, a further object being the provision of a hand controlled emergency release coupling or fastening for use under conditions in which ordinary coupling devices are in general inapplicable.

The invention is specially applicable for example for releasing the parachute or 20 parachute and harness from a person on landing after a parachute descent, as the coupling is exceedingly safe and not liable to accidental or premature involuntary release through panic, sudden fright or loss of nerve.

Broadly speaking, and considering the 25 invention in a generic sense, it will be observed that the improved coupling comprises a body for connection to one part of the life line, and a co-acting link for connection to the other portion of said line, the 30 body being recessed and the link extending into the recess to permit projection of a retractile retainer through aligned apertures in these two parts. In carrying out the invention, I propose the use of two different 35 species, each of which is generically covered by the foregoing structure.

More specifically stated, the invention 40 consists of two coupling members, a screw threaded coupling pin, carried in one of the coupling members and arranged to move into or out of engagement with the other member, and an internally screw-threaded winding reel, drum or nut, engaging the pin, and provided with a wound cord, tape 45 or the like arranged to rotate the reel, drum or nut when pulled off the same as herein-after described, and thus to cause the coupling pin to move into the uncoupling or release position.

50 In the accompanying drawings:

Figs. 1 and 2 are front and side elevations

respectively of a quick release coupling constructed according to this invention.

Fig. 3 is a vertical section taken at 3—3 60 Fig. 2.

Fig. 4 is a vertical section taken at 4—4 Fig. 1.

Fig. 5 is a transverse section taken at 5—5 Fig. 1.

Fig. 6 is a vertical section taken at 6—6 65 Fig. 4.

Fig. 7 is a diagram showing the application of the coupling to the life line of a parachute.

Figs. 8 to 10 are opposite side elevations 70 and front view of the improved coupling with line and attached leather sheath for securing the end of the releasing tape.

Fig. 11 is a side elevation partly in section of a coupling of slightly modified form 75 of construction.

Fig. 12 is a rear elevation of the same, and Figs. 13 and 14 are detail views.

As shown in Figures 1 to 9, one coupling member consists of a tongue piece or link *a* 80 having a hole *b* for attachment to one part of the life line *c* of a parachute (see Fig. 7) while the other coupling member consists of a body *d* having a bifurcation or recess for receiving the link *a*. This body is also 85

equipped with an integral support or guide cheek *e* spaced from the body to accommodate a reel *f*. A hole *g* in the depending portion of the body serves for the attachment of the other part *c* of the life line to 90 be coupled to the part *c*. In Fig. 7, the part *c'* of the life line is also shown attached to the part *c''* of a conventional form of aeronaut's harness. The reel *f* is mounted between end bearing rings *f'* and has a screw-threaded axial bore in which a removable screw-threaded coupling pin *h* is caused to 95

operate by the rotation of the reel, the said pin being arranged to move in aligned holes *i* and *i'* in the body *d* and guide cheek *e* and through a hole *j* in the link *a* to secure the parts of the coupling together. Rotation of the pin *h* is prevented by a fixed projection *k* extending into a groove *k'* in the pin, this projection being formed as shown on 100 a flanged ring *l* fixed by screws to the outer face of the cheek *e*. The ring *l* is provided with screw threaded portion which supports a casing or housing *m*, held in position by a milled nut *n*. Provision is also 105 made for securing the nut with a lead seal, for which purpose eye screws *n'* *n''* are fixed 110

in the nut and casing m for the attachment of a fastening wire n^3 with seal as shown in Fig. 2. For the purpose of sliding the coupling pin h and releasing the coupling, 5 a tape o is wound on the reel f , being attached at one end to a pin p . When pulled, the tape rotates the reel f , which being prevented from moving axially, imparts a sliding movement to the coupling pin h owing 10 to its screw threaded connection therewith. It will be understood that the free end of the tape may hang in a convenient position for operation by hand, or otherwise, or may be secured to a leather sheath as hereinafter 15 described. A suitable guide q for the tape is also preferably provided on the coupling as seen better in Figs. 3 and 6.

In order to keep the tape in wound condition on the reel a spring brake ring r is 20 interposed between the reel and the adjacent bearing ring f' and co-operates with the rings f' which may be of copper, to prevent unintended rotation of the reel.

When the coupling is applied to the life 25 line c, c' of a parachute as illustrated in the diagram Fig. 7, the free end of the releasing tape o is preferably held in a sheath s of leather or other suitable material to prevent it from being pulled accidentally 30 or involuntarily, said sheath being located in a position in the life line convenient to the hand of a person suspended therefrom. The arrangement is clearly illustrated in Figs. 8 to 10 from which it will be seen 35 that the sheath s is attached to the part c' of the life line and secured by a screw to an angle piece t on the coupling member d . The tape o passes down through the interior 40 of the upper part of the sheath and out through an opening u therein and terminates in a leather tongue piece o' which is inserted in another opening u' in the sheath. Now in order to operate the coupling it is 45 necessary to withdraw the tongue piece o' and then exert a pull on the tape which may be arranged to effect the release of the coupling only after the tape has been drawn out a predetermined distance.

In the modified form of construction 50 shown in Figs. 11 to 14, the coupling of the parts a and d is obtained by providing a pivoted cheek d' on the coupling member or body d . An integral eye piece or tubular journal g' forms the pivot of the cheek 55 d' which is locked in the closed position by a retractile retainer in the form of a spring pressed bolt v arranged to enter a hole v' in the cheek, the hole v' being countersunk to enable the bolt to be pressed back 60 and disengaged with the finger. A curved recess w is formed in the cheek d' for reception of the outer end of the coupling pin h .

It will be understood that the improved 65 quick release coupling instead of being con-

nected in the life line may form part of the fastening of the belt of a parachute harness or may be applied for coupling a passenger carrying basket with a parachute, such for example as the basket of a balloon, 70 or may be applied in various other ways, and for various other uses.

I claim:

1. A coupling comprising apertured coupling members, a coupling pin adapted to 75 project through the apertures, and means for disengaging the pin from one of said members including a reel in connection with the pin for rotating the latter, and means wound on the reel to rotate the same when 80 a pull is exerted thereon.

2. A quick release coupling consisting of two coupling members, a screw-threaded coupling pin carried in one of the coupling members and arranged to move into or out 85 of engagement with the other coupling member, an internally screw-threaded reel mounted on the coupling pin, means for preventing endwise motion of the reel, and flexible means for rotating the reel. 90

3. A quick release safety coupling for 95 coupling a parachute with its load consisting of an apertured coupling member adapted to be secured to the life line of a parachute, a co-operating apertured coupling member adapted to be secured to the load, a coupling pin adapted to engage in the apertured coupling members, and means for operating the coupling pin including a reel operatively connected with the coupling 100 pin and means adapted to be wound on the reel and to rotate the same when pulled off.

4. A coupling comprising a recessed body, one wall of the recess being formed with an aperture, a link disposed in said recess and provided with an aperture alined with the first named aperture, a retractile connector having one end projecting through said apertures, and automatically operable 105 manually controlled means for moving said connector to inoperative position. 110

5. A coupling of the class described comprising a body having a recess, a link having one end received in said recess, said link being equipped with an aperture, said body being provided with a guide cheek spaced from said body, a horizontally disposed axially retractile pin carried by said body and having one end projecting through the aperture in said link and engaged with one wall of the recess, a drum having screw-threaded connection with said pin, said drum being disposed between said cheek and body, and a flexible element wound on said drum. 115

6. A coupling of the class described comprising a body having a recess and provided at a spaced point with a vertically disposed guide cheek, a horizontal pin slidably mounted on said body and having one end 120

projectible across said recess, the opposite end of said pin being externally screw threaded and provided with a longitudinal groove, a projection carried by said cheek 5 and extending into said groove to prevent rotation of the pin but to permit longitudinal sliding thereof, a drum disposed between said guide cheek and body and having threaded connection with said pin for 10 sliding the latter, and a link having one end

disposed in said recess, said one end being provided with an aperture through which said pin is adapted to pass.

In testimony whereof he has affixed his signature, in presence of two witnesses.

HAROLD EDWARD SHERWIN HOLT.

Witnesses:

SAMUEL PERCIVAL,
WILLIAM H. DAVIS.
